UNITED STATES PATENT OFFICE.

KERSON NURIAN, OF ST. LOUIS, MISSOURI.

ARM FOR SUPPORTING WIRES.

No. 839,412.

Specification of Letters Patent.

Patented Dec. 25, 1906.

Application filed June 27, 1906. Serial No. 823,574.

To all whom it may concern:

Be it known that I, KERSON NURIAN, a citizen of the United States of America, residing in the city of St. Louis, in the State of Missouri, have invented certain new and useful Improvements in Arms for Supporting Wires, &c., of which the following is a full, clear, and exact description, reference being had to the accompanying drawings, forming part of this specification.

My invention relates to a new and useful improvement in arms for poles, walls, &c., for supporting electric wires, cables, &c., and has for its object to produce an arm which can be clamped to and unclamped from poles, walls, &c., and one which can be extended in length on one or both ends for supporting additional wires, &c.

In cross-arms with which I am familiar it has been customary to make these arms of sufficient length to carry the maximum amount of wires which it is contemplated the arms should ever be called upon to support. This construction calls for, when, say, only two wires are carried by said arms, an expense in the cost of unnecessary metal of which the cross-arm is made, and it is this expense I propose to save by the construction shown in the accompanying drawings.

Figure I is a top or plan view of my improved arm shown attached to a supporting-post. Fig. II is a side elevation of the same.

A designates a supporting-post upon which my improved arm B is attached. This arm B is composed of two analogous sections 1, which are provided upon their inner ends with preferably approximately semicircular recesses 2, which when properly positioned upon the supporting-post A and clamped thereto by means of bolts 3, which pass through perforated laterally-disposed lugs or ears 4, formed on said sections 1, produce an arm whose members extend laterally from the pole A. The outer ends of these arm-sections 1 are each provided with a preferably semicircular recess 5, and extending laterally from the outer ends of said sections are perforated lugs or ears 6. When it is intended that the arm as an entirety shall only support two wires, I employ cap-pieces 7, having recesses 8 complementary to the recesses 5 and which are provided with perforated lugs or ears 9 similar to the lugs or ears 6, and by which recesses and lugs a suitable insulator X (shown in dotted lines upon the left-hand

side of the drawings) can be secured to the ends of the sections 1.

When occasion demands that more wires should be supported upon the arm, all that is necessary to do is to remove the cap-piece or cap-pieces 7 and in its or their places secure an extension bar or bars 10, which bar or bars 10 are provided upon each end with recesses and lugs or ears, the purpose of which is manifest from an inspection of the right-hand side of the drawings, the cap-piece 7 being employed to coöperate with the outer end of this extension-bar 10.

I claim—

1. A new article of manufacture consisting of an arm constructed to receive an extension member, and an extension member constructed for attachment to said arm and arranged to have another extension member attached thereto, substantially as set forth. 70

2. A supporting-arm formed in sections and provided with means whereby it can be secured to a support, and means whereby the sections are detachably fastened together for securing in place between them an element 80 for supporting wires and the like. 75

3. An arm provided with means whereby it can be secured to a support, detachable means for securing in place an element for supporting wires and the like, and an extension-bar which can replace and perform the function of said detachable means, substantially as set forth. 85

4. An arm having a recessed end, an extension-bar having a complementary recessed end, and means for securing said arm and said extension-bar together, said means being also designed to support within the recesses of said arm and extension-bar an insulation element, substantially as set forth. 90

5. The combination with a support, of an arm carried thereby, means for supporting an insulation element upon said arm, an extension-bar, and means for supporting an insulation element upon said extension-bar, 100 substantially as set forth.

6. The combination with a support, of a sectional arm carried thereby, means for supporting an insulation element upon said arm, an extension-bar, and means for supporting an insulation element upon said extension-bar, substantially as set forth. 105

7. The combination with a support, of an arm having a recess for receiving said support, means for securing said arm to said sup- 110

port, means for supporting an insulation element upon said arm, an extension-bar, and means for supporting an insulation element upon said extension-bar, substantially as set forth.

5. 8. The combination with a support, of a sectional arm, each section of which is provided with a recess for receiving said support, means for securing said arm-sections to

said support and to each other, means for supporting an insulation element upon said arm, an extension-bar, and means for supporting an insulation element upon said extension-bar, substantially as set forth.

KERSON NURIAN.
